UNITED STATES PATENT OFFICE.

FREDERICK T. CONLEY, OF JAMAICA PLAIN, MASSACHUSETTS.

EXPANDING AND CUTTING-OFF TOOL.

1,294,404.

Specification of Letters Patent. Patented Feb. 18, 1919.

Application filed July 18, 1917. Serial No. 181,416.

To all whom it may concern:

Be it known that I, FREDERICK T. CONLEY, a citizen of the United States, residing at Jamaica Plain, in the county of Suffolk, in the State of Massachusetts, have invented a certain new and useful Improvement in Expanding and Cutting-Off Tools, of which the following is a specification, reference being had to the accompanying drawings.

10 The object of this invention is to provide a specially convenient and effective portable device for use in expanding the ends of piping and particularly small brass or copper tubing such as is used more or less commonly in connection with automobile engines and in like places, and my said invention also includes means for cutting off such tubing and for milling or knurling its circumferential surface if desired.

15 20 In order to explain my invention clearly I have provided the annexed drawings, in which Figure 1 is mainly a side elevation of an implement embodying my present improvements and Fig. 2 is a side view of the same.

25 Fig. 3 is a detached side view of the knife lever 19—20. Fig. 4 is a plan view of the frame 15 and Fig. 5 is an inner side face view of the jaw 10.

30 35 By preference, I manufacture my improved implement as a hand tool which may be of light weight, and inexpensive as to cost and which may be conveniently used, for the several features for which it is designed, either separately or collectively, that is to say a pipe end may be expanded, or cut off, or knurled, by separate operations or such pipe may be expanded, knurled and cut off.

40 45 As here illustrated, the several distinctive mechanical features of the implement are mounted co-operatively upon a pair of pliers consisting of a single jaw 10 and a bifurcated jaw 11 which jaws are fulcrumed at 12; said jaws being connected with, or formed as integral parts of operating handles 13 and 14 respectively.

50 55 The pliers thus provided are utilized for clasping a piece of pipe and holding it against rotation while it is being expanded or cut off, as the case may be. I will now describe the special means which I have provided for expanding said pipe.

Fulcrumed on the same bolt (12) which connects the two plier members 10—11 is a frame 15 in which is mounted a screw 16

whose inner end carries an expanding head 17 and whose outer end has fixed thereon a thumb-piece 18 by means of which the screw 16 may be turned during the operation of forcing the expanding head 17 into the open 60 end of a piece of pipe; the frame 15 being so swiveled on the bolt 12 that it may be readily rocked and adjusted so as to move the expanding head into register with the end of the pipe held by the jaws 10—11. 65 After having been used to expand the pipe end, the head 17 may be withdrawn from the pipe by simply unscrewing the screw 16 when the frame 15 may be swung to one side, out of the way, as seen in Fig. 1 of the 70 drawings.

The knife for cutting off the pipe end is also fulcrumed upon the screw 12, between the jaws of the pliers, said knife being of simple lever form, one of whose ends is 75 formed as a cutting edge 19, the other end consisting of a handle 20 which is so located that it may be grasped and used in conjunction with the described pliers whenever it is desired to force the end of knife 19 into 80 cutting engagement with the pipe; it being understood now that said pipe is being held against rotation by a vise or other form of clamp while the combined pliers and cutter are revolved around the pipe.

85 The hole in the plate which supports the clamp 15 is, intentionally, elongated, as seen in Fig. 4, in order that the expander screw 16 may be properly adjusted with relation to the pipe-holding jaws 10—11 and so that 90 the expander head may register with pipes of greater or lesser diameter, as the case may be.

If desired, the holding jaws of the pliers may be serrated or milled in order that they 95 may the better grip the pipe or other articles which is being clamped.

As a convenient and effective means for clamping the free ends of the handles 13—14 of the pliers in fixed relation to each other I 100 have provided a screw-threaded bolt 21 one end of which is fixed in the handle 13 and the other end has mounted thereon a thumb-nut 22 (see Fig. 1).

The operation of my described tool is as 105 follows:

If it is desired to expand the end of a tube the tube is placed between the jaws 10 and 11 and the nut 22 is screwed on the bolt 21 until the tube is held firmly by the jaws. 110

The expander head 17 is adjusted as to position until it confronts the open end of the tube, and the screw 16 is rotated in frame 15 until the head 17 is forced into the tube end 5 the desired distance, resulting in expanding or flaring the tube end. If it is then desired to cut off the flared end portion of the tube the nut 22 is eased back, sufficiently to permit the pipe to be rotated in the jaws 10—11 10 which then serve as a bearing and support for the pipe and, meanwhile the expander head serves as an end bearing, or center tool, to prevent both lateral and endwise displacement of the pipe, which latter may be held 15 fixedly in an ordinary vise. The tool (including the handle 20 of the knife 19) is then grasped and rotated bodily around the pipe until the knife cuts through the shell

of the tube and severs the expanded washer, or short pipe section, from the main pipe. 20

My described implement may be used for clamping, expanding or cutting off a pipe end; it is small and compact, and it may be manufactured at reasonably small cost.

Having thus described my invention, and 25 the manner in which it is used, I claim as new and wish to secure by Letters Patent:—

A tool of the class referred to, comprising clamping jaws, screw-threaded means for adjusting and holding said jaws with respect to each other, cutting off means consisting of a fulcrumed knife and operating handle mounted on said jaws, and screw-threaded laterally adjustable means for expanding a pipe end held by said jaws. 30

FREDERICK T. CONLEY.
